UNITED STATES PATENT OFFICE.

ALBERT HARGRAVES, OF AKRON, OHIO, ASSIGNOR TO THE FIRESTONE TIRE & RUBBER COMPANY, OF AKRON, OHIO, A CORPORATION OF OHIO.

DESIGN FOR A PNEUMATIC TIRE.

48,892.

Specification for Design.

Patented Apr. 18, 1916.

Application filed February 14, 1916. Serial No. 78,290. Term of patent 14 years.

To all whom it may concern:

Be it known that I, ALBERT HARGRAVES, a subject of the King of Great Britain, residing in Akron, in the county of Summit, State of Ohio, have invented a new, original, and ornamental Design for Pneumatic Tires, of which the following is a specification, reference being had to the accompanying drawings, forming a part thereof.

In the drawings Figure 1 is a plan view of

a portion of a tire showing my new design; Fig. 2 is a side elevation of a portion of the tire.

I claim:

The ornamental design for a pneumatic tire as shown.

ALBERT HARGRAVES.
